MINING MACHINE

Robert K. Jeffrey, Columbus, Ohio, and Lewis E. Mitchell, deceased, late of Columbus, Ohio, by Richard D. Nichols, administrator, Columbus, Ohio, assignors to The Jeffrey Manufacturing Company, a corporation of Ohio

Original application May 6, 1938, Serial No. 206,448. Divided and this application November 4, 1940, Serial No. 364,324

11 Claims. (Cl. 262—28)

This invention relates to a mining machine and particularly to mechanism for propelling a mining machine during transportation.

An object of the invention is to provide a mining machine which can be fed at a sumping speed, which speed may be varied continuously and progressively in accordance with the hardness of the material being cut.

A further object of the invention is to provide feeding means for a mining mechanism, such as a kerf cutter, including hydraulic feed mechanism in which the feed rate may be varied in a continuous manner between relatively wide limits.

A further object of the invention is to provide mechanism for selectively propelling a mining machine at a relatively high trammimg speed by direct mechanical connection from the driving motor to the traction means and to propel a mining machine at a much slower sumping speed by drive gearing between the driving motor and the traction means which includes a hydraulic pump and hydraulic motor which may be considered as a hydraulic link or coupling in the gear train.

A further object of the invention is to provide improved mechanism for driving a mining machine or other vehicle at a variety of speeds.

Still another object of the invention is to provide an improved hydraulic system for adjusting certain adjustable devices of a mining machine.

Other objects of the invention will appear hereinafter, the novel features and combinations being set forth in the appended claims.

This application is a division of our application Serial No. 206,448 filed May 6, 1938, for an improvement in Mining machines, which matured into Patent No. 2,263,779, November 25, 1941.

In the accompanying drawings:

Fig. 1 is a diagrammatic plan view showing a mining machine incorporating the structure of our invention;

Fig. 2 is a plan view of the rear end of the mining machine shown in Fig. 1;

Fig. 3 is a plan view of the truck of the mining machine showing parts in section;

Fig. 4 is a transverse sectional view taken on the line 4—4 of Fig. 2 looking in the direction of the arrows;

Fig. 5 is a transverse sectional view taken on the line 5—5 of Fig. 2 looking in the direction of the arrows;

Fig. 6 is a longitudinal sectional view showing the drive for the truck and taken on the line 6—6 of Fig. 5 looking in the direction of the arrows;

Fig. 7 is a diagrammatic illustration of the hydraulic control system of a portion of the mining machine which is the subject matter of the invention herein claimed; and

Fig. 8 is a sectional elevational view of a volume control and pressure relief valve employed in the system of our invention.

In Fig. 1 of the drawings there is illustrated diagrammatically a mining machine which incorporates the features of the invention herein claimed. The mining machine is disclosed in full detail in our parent application above identified, of which this application is a division, and so no attempt will be made to describe it in detail in its entirety, only those parts forming the subject matter of the invention herein claimed being specifically described.

Said mining machine includes a truck 45 which supports a turntable 71 upon which is mounted for adjustment in a vertical plane a supplementary frame 100 which has a forwardly extending neck 109 carrying a turnover head mechanism 159 which provides for various adjustments of kerf cutting mechanism 160.

Extending rearwardly from and supported by the truck 45 is a platform 545 which carries a considerable amount of mechanism some of which per se is not pertinent to the invention herein claimed.

The truck 45, best seen in Fig. 3 of the drawings, comprises a main frame formed by spaced apart longitudinally extending frame members 46, 46 which are laterally spaced apart and between which extend transversely extending forward plate 47 and transversely extending rearward plate 48 and intermediate transversely extending bolster members 49 and 50. All of said main frame members 46 to 50, inclusive, are rigidly attached together to form a strong main frame for the truck 45. Said main frame is supported upon a forward axle 51 and a rearward axle 52, which axle 51 is slidably journaled in adjustable journal boxes 53, 53 which may be longitudinally adjusted by adjusting screws 54, 54 to adjust the tension of the driving chain. To assure movement of the axle 51 in parallelism the adjusting screws 54, 54 are connected to rotate together by chain and sprocket mechanism 55.

The journal boxes 53, 53 are held in the main frame against longitudinal movement but provide for limited vertical movement thereby to permit the shaft 51 to move relative to the longitudinal axis of the truck 45 to provide a modified three point suspension for said truck 45 so it may readily accommodate itself to the unevenness of

the mine tracks over which the mining machine travels.

The rear end axle 52 is rigidly journaled to the main frame of the truck 45 by appropriate journal bearings 56, 56. The axles 51 and 52 are provided with appropriate driving and supporting track engaging flanged wheels 57 all of which are keyed to the respective axles 51 and 52 by keys 58. The axles 51, 52 are connected to rotate in unison by chain and sprocket mechanism 59. It is thus evident that any driving force supplied to axle 52, as hereinafter described, will be transmitted to all four of the wheels 57 thereby insuring a maximum of traction for propelling the mining machine which is particularly desirable during sumping operations. It is, of course, evident that the afore-described adjusting screws 54 provide for the tensioning of the chain and sprocket mechanism 59 by the forward and rearward adjustment of the axle 51.

It is of course evident that the flanged wheels 57 are adapted to ride upon rails in a mine either for transporting the mining machine from one place to another or for supporting said mining machine while performing a mining operation. While we prefer this track mounted type of truck said truck may be mounted in any other desired manner as upon endless treads to operate in a trackless mine room.

In addition to those elements above described the truck 45 also includes a top plate 70 which is rigidly attached to the frame members 46, 47 and 48.

Mounted upon the truck 45 for swinging movement in a horizontal plane or about an upright axis is a turntable 71. (Fig. 1.) The turntable 71 has attached at its center a casting or pedestal 75. (Fig. 3.)

To provide for the swinging movement of the turntable 71 about its upright axis with respect to the truck 45, the lower portion of the casting 75 is provided with a pair of spaced integral gears 79 with which cooperate a pair of racks 80 and 81 having spaced top and bottom teeth.

To apply turning movement to said turntable 71 through the racks 80 and 81 they are connected to hydraulic piston motors 82 and 83, respectively.

As clearly illustrated in Fig. 7 of the drawings, a pipe 95 leads to the head end of the piston motor 83 and a pipe 96 leads to the piston rod end thereof. Similarly associated with the motor 82 is a pipe 97 leading to the head end and a pipe 98 leading to the piston rod end.

As disclosed completely in said parent application, the two hydraulic piston motors 82 and 83 are always operated together and in reverse directions so that a very powerful and equalizing force will be transmitted to the turntable 71 to swing it.

As best seen in Fig. 1 of the drawings, there is mounted upon the turntable 71 for movement about a horizontal axis a supplementary frame 100 formed by a rigid motor casing 101 within which is housed an electric motor for driving the kerf cutting mechanism 160 to the forward end of which is attached a gear casing having a downwardly sloping neck 109.

Attention is now directed particularly to Fig. 7 of the drawings which illustrates diagrammatically a portion of the hydraulic control system for operating the mining machine including particularly apparatus carried by platform 545 and the control for hydraulic piston motors 82 and 83.

for swinging the turntable 71. Said hydraulic system includes a supply tank 380 for the hydraulic fluid, preferably oil, from which extends a feed pipe 381 associated with a filter 382 in the bottom of said supply tank 380. The feed pipe 381 leads to a pressure control valve 383.

Said pressure control valve 383 comprises a block provided with check valves 386 and 387 leading to chambers 388 and 389, respectively. Communicating with the chambers 388 and 389 are pipes 390 and 391, respectively, which form the feed pipe and out-put pipe, respectively, of a high pressure pump 392 which, for example, may be of the gear type and capable of producing a pressure of approximately 1500 pounds per square inch. The pressure control valve 383 also includes ball check valves 393 and 394 which communicate with chambers 388 and 389, respectively. Associated with the ball check valves 393 and 394 is pressure pipe 399 which is the main pressure pipe for the hydraulic system.

The function of the pressure control valve 383 is to insure that the pipe 381 will act as a feed pipe and that it will be under suction at all times and the pipe 399 will act as a pressure pipe and be under pressure at all times, regardless of the direction of rotation of the gear pump 392. For example, if the gear pump 392 is operated in its normal direction to draw in oil through pipe 390 and discharge oil through pipe 391, check valve 386 will be open to provide communication between pipe 381 and pipe 390 and due to the pressure in pipe 391 check valve 387 will be maintained closed. At the same time, due to the pressure in chamber 389 check valve 394 will be open to supply oil under pressure to pressure pipe 399 and check valve 393 will be held closed by the pressure to said pipe 399.

Should the pump 392 reverse its direction of rotation and draw in oil from pipe 391 and deliver oil under pressure to pipe 390, check valve 387 will open to supply oil from pipe 381 to said pipe 391 and check valve 386 will be held closed by the pressure in chamber 388. Also check valve 393 will be open due to the pressure in chamber 388 to provide communication between pipe 390 and pressure pipe 399. Furthermore, due to the pressure to said pipe 399 check valve 394 will be maintained closed. It is thus evident that pressure pipe 390 will always be the main pressure lines of the hydraulic system and that pipe 381 will always be the main feed line of the hydraulic system without regard to the direction of rotation of pump 392.

The pressure pipe 399 leads to a volume control and pressure relief valve 400 which, as its name indicates, acts to control the volume of fluid delivered to the hydraulic system by the pump 392 and to relieve the pump 392 in case a predetermined high pressure is reached. The structure of this volume control and pressure relief valve 400 is illustrated in detail in Fig. 8 of the drawings, to which attention is now directed.

Said valve comprises a main block 401 provided at its bottom with a cylindrical chamber 402 with which the pressure pipe 399 communicates and within which is a rotary control cylinder 403 having a removed portion 404 and carried on a shaft 405 with which is associated an operating lever 406 to adjust the position of the control cylinder 403 in the chamber 402. By adjusting the cylinder 403 the size of the opening afforded between inlet port 407 and outlet port 408 of the chamber 402 may be regulated thereby controlling the volume of fluid which flows from the

pressure pipe 399 to the pressure pipe 409 leading from the volume control and pressure relief valve 400 which pressure pipe 409 is in communication with the outlet port 408. It is thus evident that the operating lever 406 may be adjusted to control the normal volume of hydraulic fluid to be supplied to the pressure pipe 409.

Associated with the pressure pipe 409 is a pipe 410 which leads to a pressure gauge 411 which will, of course, indicate the pressure in the pressure pipe 409 at all times.

To provide for the high pressure relief feature of the valve 400 the block 401 is provided with a cylindrical chamber 412 the bottom of which is in communication with the inlet port 407 and above which port 407 is a circumferential chamber 413. Within the chamber 412 is a piston 414 urged to bottom seating position by a coil spring 415, the top of which rests against a plug 416 threaded in the top of block 401. A connecting pipe 417 leads from the pipe 410 to a bore 418 of restricted size which communicates with the chamber 412 at a position above the piston 414.

Also communicating with the chamber 412 at a position above piston 414 is a larger bore 419 leading to a chamber 420 which is connected by a vertical bore 421 to a drain pipe 422 which also communicates by a bore 423 with the chamber 413. Within the chamber 420 is a ball relief valve 424 provided with a compression spring 425, the compression of which may be adjusted by adjusting screw 426.

In normal operation the piston 414 automatically assumes a floating position in chamber 412 to by-pass just enough hydraulic fluid to maintain a fluid flow from pipe 399 to pipe 409 through the adjustable orifice, provided by removed portion 404, to maintain said piston 414 in a condition of equilibrium, whereby it will operate to by-pass an amount of hydraulic fluid as determined by the adjustable position of handle 406 to insure delivery of a variable predetermined amount of hydraulic fluid at all times, under the control of the operator, to the said pipe 409, the remaining portion of the hydraulic fluid delivered by the pump 392 to the pipe 399 being by-passed by way of port 407, chamber 413 and bore 423 to drain pipe 422. The delivery rate to pipe 409 is therefore determined solely by the position of handle 406.

The adjustable pressure drop across the adjustable orifice provided by removed portion 404 is of course the controlling factor in maintaining this condition of equilibrium because this pressure drop is supplied to the floating piston 414. Any decrease in fluid flow to pipe 409 from that required by the setting of handle 406 will cause the piston 414 to move downwardly thereby reducing the amount of liquid by-pass from pipe 399 to drain pipe 422 which will immediately correct this condition. Conversely, any increase in fluid flow to pipe 409 from that required by the setting of arm 406 will cause the piston 414 to move upwardly thereby increasing the amount of liquid by-passed from pipe 399 to drain pipe 422 which will correct this condition.

The valve 400 has a high pressure relief function by virtue of ball relief valve 424. For example, should the pressure in the pipe 409 exceed 12,000 pounds per square inch, or any other amount depending upon the setting of ball relief valve 424, said relief valve 424 will open to permit fluid under pressure in the chamber 412 to flow through bores 419 and 421 to drain pipe 422.

The opening of valve 424 may be due to a

gradual increase in pressure communicated through bore 418 or to a sudden increase which will move piston 414 upwardly since the pressure above it will not be equalized immediately due to the drop through said bore 418.

When ball valve 424 opens, reduced pressure is provided above piston 414. The higher pressure below piston 414 then lifts it. As a consequence of any of the above conditions the piston 414 will be lifted above its normal position to permit more or all of the fluid under pressure in port 407 to flow to the chamber 413 and thence to drain pipe 422 by way of bore 423.

It is evident that after a high pressure condition is relieved, the relief valve 424 will operate to close the bore 419 thereby to restore said piston 414 to its normal condition.

As a safety feature we also provide a by-pass around the relief valve 424 which may be manually operated in case said relief valve becomes inoperative for any purpose. This by-pass is formed by a pipe 427 communicating with bore 419 and extending to manually operated relief pilot valve 428, the structure of which is disclosed in full detail in our parent application above identified.

Thus should any emergency arise in which the automatic pressure relief function of the valve 400 is not performed, it may be relieved by the manual operation of the relief pilot valve 428 which interconnects pipes 427 to a drain pipe 440 leading to drain pipe junction box 441.

It may also be noted at this point, by reference to Fig. 7 of the drawings, that a drain pipe 442 extends between the pump 392 and the junction box 441 to provide for the return of any oil which does not flow in the proper path, particularly such oil as leaks past bearings or bushings.

From that portion of the hydraulic control system above described it is manifest that hydraulic fluid under regulated pressure and volume is supplied to the pressure pipe 409 which, as clearly illustrated in Fig. 7 of the drawings, leads to a two unit control valve 443 which has two manually operable control pistons. It may be stated that the two unit control valve 443 has one slide piston 520 (Fig. 4) which is operative to control the hydraulic piston motors 82 and 83 for swinging the turntable 71 about its upright axis; and another slide piston 519 which is operative to control a rotary type of hydraulic motor 444 to effect slow speed or sumping travel of the mining machine, as hereinafter described in complete detail.

It may also be stated that excess fluid drain pipes 445 and 446 are provided for the control valve 443 and hydraulic motor 444, respectively, which lead to the junction box 441 and, in turn, to the drain pipe 422.

It may also be stated that without regard to the positions of the slide pistons 519, 520 of the two unit control valve 443, pressure will always be available to a flexible rubber hose pressure pipe 447 which extends therefrom and leads to further hydraulic control valves disclosed completely in our parent case which per se are not pertinent to the invention herein claimed. Slide piston 519 controls the flow of hydraulic fluid under pressure from pressure pipe 409 by way of pipe 522 or 523 to rotary sumping hydraulic motor 444 for driving the mining machine at a slow sumping or kerf cutting speed, as hereinafter described, and slide piston 520 controls the flow of fluid under pressure from pressure pipe 409 from the afore-described control unit 400 by way of pipe 524 or 525 to the hydraulic piston motors 82 and 83 which

are reversely connected in parallel to swing the turntable 71. It is to be understood that reverse operations of the two mentioned slide pistons 519 and 520 will produce a reverse operation of the motor 444 in the one instance and of the motors 82 and 83 in the other instance. It is also to be understood that when in their normal positions the slide pistons 519 and 520 will lock the motor 444 and the motors 82, and 83, respectively, in their adjusted positions and provide a no-load by-pass for pump 392.

As clearly seen by reference to Figs. 2 and 4 of the drawings, in the corner provided by the side plate 547 and the supplementary rearward plate 551 of the platform 545, the hydraulic fluid supply tank 380 is supported. Adjacent the opposite forward corner of the platform 545 and supported upon the supplementary rearward plate 551 is the two unit control valve 443. The volume control and pressure relief valve 400 and the relief pilot valve 428 are likewise carried on the supplementary rearward plate 551 near the two unit control valve 443. The pressure gauge 411 is supported by the supplementary side plate 550 which is provided with a window 552 (see Fig. 4), so that said gauge may be easily read.

It is to be noted by reference to Figs. 2 and 4 that a pair of operating means 553 and 554 are associated with the slide pistons 519 and 520, respectively, of the two unit control valve 443 each of which comprises a pivoted lever pivoted to a bracket 555 and extending respectively through slots 556 and 557 in the plate 551 whereby they will be readily accessible at a position adjacent the turntable 71 where other controls are located. As a consequence, the mining machine operator will have the control levers for both the unit control valves which are carried by the supplementary frame 100, and the two unit control valve 443, which is carried by the platform 545, close at hand so that they can be easily controlled. In this connection it may be stated that all of the hydraulic system which is disclosed in Fig. 7 is carried by and moves with the platform 545, the rest of said hydraulic system which is not illustrated being carried by the supplementary frame 100. It is for this purpose that the pressure pipe 447 and the drain pipe 449 are both made of rubber hose since there is, of course, appreciable movement of the supplementary frame 100 both about a horizontal axis and a vertical axis with respect to the platform 545. It is to be noted, however, that only these two hoses extend between these relatively movable parts.

Referring again to Fig. 4 of the drawings, it is to be noted that at their right hand ends each of the slide pistons 519 and 520 is provided with automatic spring controlled centering mechanisms 559 and 560, respectively, which operate automatically to center said slide pistons 519 and 520 whenever they are released.

Referring now particularly to Figs. 2 and 4 it is seen that supported from a bottom plate 546 of the platform 545 is an electric motor 561 with which is associated control mechanisms in control box 562 and starting resistors in resistor box 563. The electric motor 561 is for driving the mining machine both at transportation and sumping speeds through the mine and for operating the oil pump 392 to provide hydraulic fluid, such as oil, under pressure to the previously described hydraulic control system. The electric motor 561 drives gear mechanism supported upon platform 564 (see Fig. 4) supported from the bottom plate 546 and comprising a pinion 565

(Fig. 2) keyed to the armature shaft of said electric motor 561. Pinion 565 meshes with two gears 566 and 567, the latter of which is keyed to a counter-shaft 568 (Fig. 4) which is journaled in housing 569 by spaced ball bearings 570 and 571. Surrounding the counter-shaft 568 and mounted for free rotation with respect thereto is a sleeve 572 mounted in housing 569 upon ball bearings 573 and 574. Keyed to said sleeve 572 is a worm gear 575 meshing with a worm 576 which is driven through gear reduction mechanism 577 from the rotary type hydraulic motor 444 (Fig. 2), previously described.

It will be noted by reference to Fig. 2 of the drawings that the gear housing 569 and the housing of gear reduction mechanism 577 are rigidly connected together and are rigidly connected to the housing of rotary hydraulic motor 444 whereby they will all be supported from the platform 564.

Also surrounding the counter-shaft 568 is a sleeve 578 mounted on said shaft 568 by roller bearings 579 and 580. Intermediate its ends the counter-shaft 568 is provided with a plurality of dogs or jaws 581, for the purpose of effecting a driving relation with the sleeve 578 by way of cooperating jaws 582 formed on slide sleeve 583 which is feathered to the outer portion of sleeve 578 by cooperating key-ways and keys 584. The jaws 582 are also adapted to cooperate selectively with jaws 585 on sleeve 572 to effect a driving relation between sleeves 572 and 578. It is evident that in the central position of the jaws 582, as illustrated in Fig. 4 of the drawings, neither the sleeves 572 and 578 nor the shaft 568 and the sleeve 578 are connected together. This, of course, represents a neutral position.

Operating means for the sleeve 583 takes the form of a shipper 586 operable by a pivoted bell crank 587 (see Fig. 2), pivoted to a bracket 588 and operable from a rod 589 which, in turn, is operated from rod 590 through pivoted bell crank 591, which rod 590 is controlled by crank 592 on the end of rod 593 supported in appropriate journals in bracket 594 and operable by handle 595 which is adjacent operator's seat 596 at the rear left-hand corner of the platform 545. It is thus evident that by controlling the handle 595 a driving connection may be made to the sleeve 578 from the electric motor 561 through the gears 565 and 567, the shaft 568 and jaws 581 and 582, or from the rotary hydraulic motor 444 through the gear reduction mechanism 577, worm 576 and worm gear 575, sleeve 572 and jaws 582 and 585. The former drive is employed as a high speed drive for the mining machine for transportation purposes and the latter drive is employed for a low speed or sumping drive when the mining machine is cutting a kerf.

It may be stated that in normal operation, the jaws 582 will engage either jaws 581 or 585 so that either a high speed or a low speed connection will be effected at this point. To maintain either of the mentioned driving relations the bell crank lever 587 has associated with it spring compression mechanism 597 operative to urge the slide sleeve 583 either to the right or to the left as the arm of the bell crank lever 587 passes to either side of the vertical alignment with spring compression mechanism 597, as will be evident from reference to Fig. 2 of the drawings. This spring compression mechanism will not only maintain the jaws in locked relation but will aid their movement into interlocking relation under the controlling influence of operating handle 595.

Adjacent its outer end the sleeve 578 is provided with an integral gear 598 which meshes with a large gear 599 (see Figs. 2 and 5), provided with a large hub 600 having spiral jaws 601 and keyed to a second counter-shaft 602 journaled in bearings 603 and 604 carried by upright plates 605 and 606, respectively, the former of which is supported from bottom plate 546 and the latter of which is supported from platform 564.

Loosely journaled on the counter-shaft 602 is a drive sprocket 607 provided with jaws 608 adapted to be engaged with and disengaged from jaws 609 of clutch sleeve 610 keyed to and slideable on counter-shaft 602 by a pivoted shipper 611 pivoted on shaft 612 and operable by rod 613 (see Fig. 2) which may be adjusted longitudinally of itself by handle 614 which may be placed on either side of stop lug 615 carried on the top of control box 562. It will be evident that by moving handle 614 to one side of stop lug 615 the jaws 608 and 609 will be engaged and by moving it to the other side they will become disengaged. It is by virtue of this clutch that the operating or non-operating connection is made for driving the mining machine either at a summing or transportation speed.

Below the drive sprocket 607 is a pair of guide and tensioning sprockets 616 and 617 (Figs. 5 and 6) mounted on shafts 618 and 619, respectively, both of which are carried by a pivoted chain adjusting arm 620 pivotally mounted by pin 621 on a pair of upright plates 622 and 623 supported from bottom plate 546, the free end of which arm 620 has cooperating therewith a chain adjusting set screw 624 which may be adjusted to swing said arm 620 about the axis of pin 621.

Reeved about the sprockets 607, 616 and 617 and about a sprocket 625, keyed to the rearward axle 52 of the truck 45, is a drive chain 626, the lower run of which is supported intermediate the sprockets 616 and 625 by a bearing pad 627 and the upper run of which is supported intermediate the sprockets 617 and 625 by bearing pad 628. It is evident that by swinging the arm 620 about the pin 621 under the influence of the set screw 624 the tension of drive chain 626 may be adjusted. It is to be particularly noted that the drive chain does not extend in a straight line between the sprocket 607 and the sprocket 625 but is generally L-shaped. This provides for a relatively large amount of adjustment in the length of the chain 626 so that the distance between the axle 52 and the shaft 602 need not be determined with extreme accuracy. It all provides for a relatively large take-up which may be caused by stretching of the chain 626 so that a complete link of the chain 626 may be removed without extending beyond the limits of adjustment thereof afforded by the arm 620.

Also associated with the previously described hub 600 of the gear 599 and feathered to the outside thereof is a clutch sleeve 630 having spiral jaws 631 adapted to be selectively placed in engagement with or disengagement from the jaws 601 of said hub 600 to effect a driving connection between said hub 600 and a chain sprocket 632 and for driving an electric cable reel mechanism 659. Shifting movement of the clutch 630 is effected by a pivoted spring pressed shipper 633 holding jaws 601 and 631 normally engaged and pivoted to shaft 634 and operable by rod 635 and crank 636 carried at the end of shaft 637 appropriately journaled in bracket 594 and 75

having an operating handle 638 associated therewith which is adjacent the previously described operating handle 595 for controlling the slide sleeve 583.

5 Gear 639 meshes with a large gear 640 (see Fig. 2) formed integral with steel cable drum 641 journaled on shaft 642 carried by side plate 547 and an upright plate 643. The drum 641 carries a steel cable 644 which is particularly useful in case the mining machine is operated in very hard coal in which case it is employed to supplement the drive effected by wheels 57 or, in case the mining operation is being carried on up a slope. The cable 644 is adapted to be reeved about guide pulleys 645 or 646 at opposite sides of the platform 545 which are preferably journaled on pivoted brackets 647 and 648, respectively.

It will be noted by reference to Fig. 5 of the drawings, that the gear 639 is feathered on the end of shaft 602 for sliding movement along the axis thereof to be brought into mesh with gear 640 or brought out of mesh therewith. To effect this sliding movement of gear 639 we provide a shipper 649 adapted to slide upon rod 650 provided with retaining notches 651 and 652 with which a spring pressed detent 653 is adapted to be selectively inserted. An operating handle 654 is provided for the detent 653. It will be evident that when detent 653 is in notch 651 there will be a driving relation between gears 639 and gears 640 and when detent 653 is in notch 652 this driving relation will no longer exist.

35 It is furthermore to be noted by reference to Fig. 5 of the drawings, that the gear 566 which is driven from pinion 565 (Fig. 2) has an integral shaft 655 mounted in anti-friction bearings 656 in upright plate 606 and is keyed to a drive shaft 657 of the hydraulic pump 392 of the previously described hydraulic control system. It is thus to be noted that whenever the electric motor 561 is in operation the hydraulic pump 392 will be in operation to supply hydraulic fluid, such as oil under pressure, to the hydraulic control system. It is furthermore to be noted, that this is entirely independent of the operation of the electric motor on supplementary frame 100 which drives the kerf cutting mechanism 160. In other words, the drive for moving the mining machine along the mine track is entirely independent of the drive of the kerf cutting mechanism.

55 As was previously pointed out, rotation of the turntable 71 about an upright axis with respect to the truck 45 is effected by the piston motors 82 and 83 which are controlled by the two unit control valve 443 and particularly by slide piston 520 thereof controlled by an operating means 554 (Fig. 4) which is adjacent the forward left-hand end of platform 545 and close at hand to the operating station.

65 It is also desirable to be able to control said hydraulic motors to swing the turntable 71 from the operator's seat 596 as the mining machine is transported along the mine tracks through the mine, particularly to adjust the supplemental frame 100 and the kerf cutting mechanism 160 to round curves in the mine. Therefore, we provide at the opposite end of slide valve 520 a pivoted operating bell crank 716 (see Figs. 2 and 5) operable by rod 717 which is controlled by handle 718 positioned near the handles 595 and 638, all of which are readily operable by an operator on seat 596 where the operator will ride when the mining machine is being trans-

ported through the mine. It may additionally be pointed out that control handles 719 and 720 are provided within reach of the operator on seat 596 for controlling the motors 561 and the motor on supplementary frame 100.

In the operation of the mining machine it may be pointed out that the motor 561 is the primary source of power for effecting all adjustments, including all feeding of the machine both while tramping and while sumping. The kerf cutting mechanism 160, however, alone is not driven from the motor 561 but is driven by a separate motor carried on supplementary frame 100 as fully disclosed in complete detail in our parent application above identified.

From a broad description it is evident that to effect a tramping speed of movement of the mining machine by which it is of course transported from one position in the mine to another position, there is a direct connection between the reversible electric motor 561 and the traction wheels 57 or endless traction treads, in case they are substituted for wheels 57. During this type of operation the drive is from pinion 565 of motor 561 through gear 567, shaft 568, jaws 581 and 582 which are in operative relation, sleeve 578 intermeshing gears 598 and 599, shaft 602, engage jaws 608 and 609, sprocket 607, chain 626, sprocket 625 and rear shaft 52 which, as previously described, is keyed to rear wheels 57 of the truck 45. Shaft 52 as above described is also connected to drive front shaft 51 through chain and sprocket drive mechanism 59 whereby all four wheels of the truck 45 are driven. This gear train is of course entirely mechanical and it may be noted that it involves two clutches, one having jaws 581, 582 (Fig. 4) the other having jaws 608, 609. Jaws 581 and 582 are normally engaged. Jaws 608 and 609 are normally disengaged. Before the motor 561 is started by way of its electrical contactors and resistors, jaws 608 and 609 are engaged when a high speed or tramping speed of transportation is desired. In case jaws 608 and 609 are disengaged it is impossible to operate the mining machine by means of traction wheels 57 and these jaws are disengaged whenever the machine is positioned adjacent a mine face to perform a mining operation. It is possible to feed the mining machine even with the jaws 608, 609 disengaged by means of the steel cable 644 in a manner which is obvious from the above description, and this cable 644 may be used either alone or with the traction wheels 57 to effect sumping feeding of the machine.

To effect a sumping feeding operation through track wheels 57 or any other traction devices which may be substituted for them the driving connection from motor 561 is through pinion 565, gear 566, pump 392 which provides hydraulic fluid under pressure over the system disclosed in Fig. 7 by which motor 444 is driven under the control of the operator and by way of slide piston 519 of control valve 443. The hydraulic pump 392 and hydraulic motor 444 when operatively connected therefore constitute a hydraulic linkage in this drive system or gear train. The gear train continues from hydraulic motor 444 through gear reduction mechanism 577, worm 576, worm gear 575, jaws 585 and 582 which are engaged to effect this driving operation by shifting of the latter jaws as above described.

The gear train then continues from jaws 582 over exactly the same path previously traced for the complete mechanical coupling which was

effected for high speed or tramping operation. Of considerable importance is the fact that the speed ratio between the electric motor 561 and the traction wheels 57 may be varied in a continuous manner by virtue of the hydraulic link effected by pump 392 and hydraulic motor 444 and the control mechanism so that the sumping speed may be adjusted in a continuous manner over a relatively wide range between the maximum sumping speed possible and substantially zero sumping speed. This speed adjustment is effected by the simple expedient of adjusting handle 406 of the volume control mechanism 400. As this adjustment provides a variable orifice or opening which is continuous in its variation, that is, it is not a step by step adjustment, the speed variation possible is a smooth continuous curve. This speed variation is of course effected by virtue of the fact that the volume of liquid delivered to the motor 444 from the pump 392 is automatically adjusted by adjusting the handle 406 of volume control mechanism 400 and of course the speed of rotation of hydraulic motor 444 is determined by the volume of hydraulic fluid which is delivered to it per unit of time.

It is also to be noted that this variable rate of operation is not confined to the motor 444 but also extends to the piston motors 82 and 83 which swing the turntable 71 and consequently the swing feed rate of the kerf cutting mechanism 160 may be variably adjusted between wide limits in exactly the same manner that the feed rate of the kerf cutting mechanism 160 is adjusted by adjusting the sumping feed rate of the entire mining machine.

It is thus evident that a very flexible drive mechanism has been provided and one which provides for a highly desirable adjustable feed rate for the mining machine and for the kerf cutting mechanism, both during rectilinear feeding of said kerf cutting mechanism and during swinging feeding thereof.

Obviously those skilled in the art may make various changes in the details and arrangement of parts without departing from the spirit and scope of the invention as defined by the claims hereto appended, and we therefore wish not to be restricted to the precise construction herein disclosed.

Having thus described and shown an embodiment of our invention, what we desire to secure by Letters Patent of the United States is:

1. In a mining machine, the combination with a supporting frame, of propelling mechanism therefor comprising a countershaft, a driven element mounted for free rotation on the axis of the countershaft, a drive element also mounted for free rotation on the axis of said countershaft, a motor connected to said countershaft to drive the same, another motor connected to said drive element to drive the same, and clutch mechanism for selectively connecting said countershaft or said drive element to said driven element and thereby secure operation of the propelling mechanism from either of said motors.

2. In a mining machine, the combination with supporting framework, of mining mechanism mounted thereon, means for driving said mining mechanism, fluid-pressure operated mechanism for feeding said mining mechanism by propelling the entire mining machine including a control valve, and means for regulating the rate of feed at any predetermined maintained value between the maximum rate and zero by controlling the

volumetric flow of the fluid-pressure medium when said control valve is fully open.

3. In a mining machine, the combination with a main frame, of a kerf cutter thereon traction means for propelling said mining machine, mechanism for driving said traction means comprising a primary driving motor, a high speed drive comprising a disconnectable mechanical gear train interconnecting said motor and said traction means, a low speed drive comprising a disconnectable gear train interconnecting said motor and said traction means including a hydraulic pump driven by said primary driving motor, a hydraulic motor, drive gearing connecting said hydraulic motor to said traction means, and control means for said hydraulic motor including mechanism to vary the rate of hydraulic fluid delivery from said pump to said hydraulic motor by controlling a by-pass for said pump.

4. In a mining machine, the combination with a main frame, of a kerf cutter thereon, traction means for propelling said mining machine, mechanism for driving said traction means comprising a primary driving motor, a disconnectable gear train interconnecting said motor and said traction means including a hydraulic pump driven by said primary driving motor, a hydraulic motor, drive gearing for connecting said hydraulic motor to said traction means, and control means for said hydraulic motor including mechanism to vary the rate of hydraulic fluid delivery from said pump to said hydraulic motor by controlling a by-pass for said pump.

5. In a mining machine, the combination with a main frame, of a kerf cutter thereon, traction means for propelling said mining machine, mechanism for driving said traction means comprising a primary driving motor, a disconnectable gear train interconnecting said motor and said traction means including a hydraulic pump driven by said primary driving motor, a hydraulic motor, drive gearing connecting said hydraulic motor to said traction means, and control means for said hydraulic motor including mechanism to vary the rate of hydraulic fluid delivery from said pump to said hydraulic motor.

6. In a mining machine, the combination with a main frame, of mining mechanism thereon, traction means for propelling said mining machine, mechanism for driving said traction means comprising a primary driving motor, a gear train interconnecting said motor and said traction means including a hydraulic pump driven by said primary driving motor, a hydraulic motor, drive gearing for connecting said hydraulic motor to said traction means, and control means for said hydraulic motor including mechanism to vary the rate of hydraulic fluid delivery from said pump to said hydraulic motor by controlling a by-pass for said pump.

7. In a mining machine, the combination with a main frame, of mining mechanism thereon, traction means for propelling said mining machine, mechanism for driving said traction means comprising a primary driving motor, a high speed drive comprising a disconnectable mechanical gear train interconnecting said motor and said traction means, a low speed drive comprising a disconnectable gear train interconnecting said motor and said traction means including a hydraulic pump driven by said primary driving

motor, a hydraulic motor, drive gearing for connecting said hydraulic motor to said traction means, and control means for said hydraulic motor including mechanism to vary the rate of hydraulic fluid delivery from said pump to said hydraulic motor and operative thereby to control the feed rate of said machine while said mining mechanism is in operation.

8. In a mining machine, the combination with 10 a supporting framework, of mining mechanism mounted thereon means for driving said mining mechanism, hydraulic mechanism for feeding said mining mechanism by propelling the entire mining machine including a source of hydraulic fluid under pressure, a control valve, a hydraulic motor, and means for variably adjusting the feed rate of said mining mechanism to any one of a plurality of predetermined maintained speeds when said control valve is in its normal open position, said last named means including an adjustable member, there being a predetermined maintained speed for each position of adjustment of said adjustable member.

9. In a mining machine, the combination with 25 a supporting framework, of mining mechanism mounted thereon, means for driving said mining mechanism, hydraulic mechanism for feeding said mining mechanism by propelling the entire mining machine including a source of hydraulic fluid under pressure, a control valve, a hydraulic motor, and a volume control valve for variably adjusting the feed rate of said mining mechanism to any one of a plurality of predetermined maintained speeds when said control valve is in its normal open position said volume control valve including an adjustable member, there being a predetermined maintained speed for each position of adjustment of said adjustable member.

10. In a mining machine, the combination with 30 a supporting framework, of a kerf cutter having an endless bit carrying cutter chain, a motor for driving said cutter chain, hydraulic mechanism for feeding said kerf cutter by propelling the entire mining machine including a source of hydraulic fluid under pressure, a control valve, a hydraulic motor, and means for variably adjusting the feed rate of said kerf cutter to any one of a plurality of predetermined maintained speeds when said control valve is in its normal open position there being a predetermined maintained speed for each position of adjustment of said adjustable member.

11. In a mining machine, the combination with 35 a supporting framework, of a kerf cutter having an endless bit carrying cutter chain, a motor for driving said cutter chain, hydraulic mechanism for feeding said kerf cutter by propelling the entire mining machine including a source of hydraulic fluid under pressure, a control valve, a hydraulic motor, and a volume control valve for variably adjusting the feed rate of said kerf cutter to any one of a plurality of predetermined maintained speeds when said control valve is in its normal open position, said volume control valve including an adjustable member, there being a predetermined maintained speed for each position of adjustment of said adjustable member.
